Primary Examiner — Prabhakar Deshmukh*(74) Attorney, Agent, or Firm* — St. Onge Steward Johnston & Reens LLC**(57) CLAIM**

The ornamental design for a window latch bolt, as shown and described.

DESCRIPTION

FIG. 1 is a front perspective view of a window latch bolt showing our new design;

FIG. 2 is a top plan view thereof;

FIG. 3 is a bottom plan view of thereof;

FIG. 4 is a front elevational view thereof;

FIG. 5 is a back elevational view thereof; and,

FIG. 6 is an end elevational view thereof, as from the left hand end of FIG. 2.

The broken lines shown in FIGS. 1-6 are for illustration purposes only and form no part of the claimed design.
